UNITED STATES PATENT OFFICE.

BIRCHARD E. HOLTON, OF LOS ANGELES, CALIFORNIA.

NOZZLE FOR AIR BRUSHES.

Application filed April 29, 1920. Serial No. 377,660.

To all whom it may concern:

Be it known that I, BIRCHARD E. HOLTON, a citizen of the United States, residing at Los Angeles, in the county of Los Angeles and State of California, have invented new and useful Improvements in Nozzles for Air Brushes, of which the following is a specification.

This invention is a nozzle for air brushes, and has for its object the provision of a nozzle arranged so that either a straight spray of the coating material or a fan-shaped spray may be applied by the air brush.

The invention will be readily understood from the following description of the accompanying drawings, in which—

Figure 1 is a side elevation, partly broken away, of an air brush having the improved nozzle.

Fig. 2 is a top plan view of the nozzle, partly broken away, with the nozzle turned to form a fan-shaped spray.

Fig. 3 is a longitudinal section on the line 25 3—3 of Fig. 2.

Fig. 4 is a transverse section on the line 4—4 of Fig. 2.

Fig. 5 is a view similar to Fig. 4 with the nozzle turned to produce a straight spray.

Fig. 6 is a view similar to Fig. 3 of a modified form of the invention.

The air brush to which the improved nozzle is applied may comprise a usual receptacle 1 forming a reservoir for the liquid to be applied by the brush and having the discharge nozzle 2 for said liquid, preferably, arranged upon the top of the receptacle. This discharge nozzle is, preferably, adjustable in usual manner for controlling the amount of the liquid discharged therethrough. The air nozzle for the brush is also mounted upon the top of the receptacle 1 and is arranged to discharge a blast of air across the end of nozzle 2 for forcing the liquid from the receptacle through the discharge nozzle and against the surface which is to be coated.

The air nozzle is shown as comprising a casing 3 having a main conduit 4 communicating with an off-set conduit 5 by way of a cross conduit 6. A pipe 7 connects the conduit 5 with the usual valve controlled connection leading to an air hose 8. This connection comprises a conduit 9 controlled by the valve 10 having a manually actuated valve stem 11 for controlling the amount of

air passing from the air hose through the air nozzle.

The air discharged from conduit 4 of the air nozzle across the end of the liquid discharge nozzle is arranged to be forced straight across said liquid discharge nozzle for producing a straight spray, or is arranged to be discharged from diametrically opposite points along converging lines toward the mouth of the liquid discharge nozzle and across the same for producing a fan-shaped spray.

As an instance of this arrangement a cap 13 having the discharge nipple 14 in the end thereof is arranged to be received over the end of the nozzle casing through which the conduit 4 extends with the discharge nipple forming a longitudinal continuation of the conduit 4. The cap is, preferably, connected to the casing by a threaded connection 15 so that the cap is free to rotate upon the nozzle casing. The rotation of the cap relative to the nozzle casing is, preferably, limited to a quarter turn as by means of a pin 16 threaded in the nozzle casing and projecting radially therefrom and received in a notch 17 provided in the edge of the cap 13, the parts being so arranged that when the cap is turned the pin, by abutment 18 against one or the other of the ends of the notch 17, will limit the turning movement of the cap to a quarter turn.

When it is desired to produce a straight spray the air from conduit 4 is discharged through the nipple 14 only, thereby producing a straight blast across the end of the liquid discharge nozzle. When, however, it is desired to form a fan-shaped blast, the discharge nipples 18 are caused to communicate with the conduit 4. These nipples shown as two in number extend laterally from diametrically opposite sides of the cap 13, as clearly shown in Fig. 2 and are then bent toward the discharge end of the air nozzle and converge toward the discharge nipple 14.

By this arrangement it will be seen that if air is discharged through both the nipple 14 and the nipples 18, a converging blast of air is produced which, after the converging currents have crossed, will produce a diverging fan-shaped blast. The air discharge nozzle is so positioned relative to the liquid discharge nozzle that the point of crossing of the converging currents will be approximately above the end of the liquid

discharge nozzle so that the spray of liquid formed by the air brush will be of the shape of the afore mentioned fan-shaped blast.

The discharge nipples 18 extend through the cap 13 and the latter is provided with diametrically opposite ports 19 arranged, when the cap 13 is turned to one of its limits of turning movement, to communicate with the respective nipples 18 so that the air from conduit 4 may be discharged through both nipples 18 and the nipple 14, thereby forming the fan-shaped blast, as previously described. When, however, the cap 13 is turned to its other limit of turning movement the ports 19 are out of communication with the nipples 18, and as a consequence the air blast from conduit 4 will be discharged through nipple 14 only, thereby producing a straight blast.

In the modification of the invention illustrated in Fig. 6 the air blast and the coating material are discharged through the same nozzle, this nozzle being arranged to produce either a straight spray or a fan-shaped spray, as previously described. In this form of the invention the nozzle casing 3' has a main conduit 4' communicating with a pipe 25 through which the coating material is supplied. The conduit 4' also communicates with an offset conduit 5' by way of a cross conduit 6'. The air is supplied through conduit 5' which for this purpose is shown connected to a pipe 7'. The supply of air and coating material through their respective supply pipes may be controlled by any suitable valve mechanism, not shown, to obtain the desired proportion of air to coating material.

The casing 3' is provided with means, such as previously described, for discharging the mixture of air and coating material from conduit 4' either through a central discharge nipple 14' for forming a straight spray or through both this nipple and the laterally and then inwardly converging discharge nipples 18' to produce a fan-shaped blast. It will be understood that the nipple

14' is carried by a cap 13', such as previously described, and arranged to be rotated by a quarter turn upon the casing 3' so as to open or close nipples 18' to the conduit 4', as previously described.

By the construction as thus set forth it will be seen that I produce a nozzle for an air brush by means of which the liquid spray produced by the air brush may be readily changed from a straight spray to a fan-shaped spray, the nozzle, as thus constructed, being either an air nozzle arranged to discharge across the end of the liquid discharge nozzle for producing a liquid spray, or a combined liquid and air discharge nozzle.

It will be further observed that the improved nozzle thus arranged to produce either a straight or fan-shaped spray is also adapted to have the proportion of liquid in the spray varied as may be found desirable.

Various changes may be made without departing from the spirit of the invention as claimed.

What is claimed is:

A nozzle of the character described comprising a casing, a threaded and shouldered extension formed on the casing, said casing and extension being formed with a conduit and diametrically disposed ports formed in the extension and communicating with the conduit, a cap threadedly mounted on the extension and abutting said shoulder, the inner end of said cap being formed with a recess, a discharge nipple within the cap and in axial alinement with said conduit, divergently arranged nipples sustained on the cap and adapted to communicate with said ports when the cap is in a predetermined position, and a pin mounted in the casing and engaging within said recess for defining the rotational movement of the cap in either direction.

In testimony whereof I have signed my name to this specification.

BIRCHARD E. HOLTON.
